CLAIM

The ornamental design for an armrest, as shown and described.

DESCRIPTION

FIG. 1 is a perspective view of an armrest showing a first embodiment of our new design;
FIG. 2 is a front view of the first embodiment;
FIG. 3 is a rear view of the first embodiment;
FIG. 4 is a left side view of the first embodiment;
FIG. 5 is a right side view of the first embodiment;
FIG. 6 is a top view of the first embodiment;
FIG. 7 is a bottom view of the first embodiment;
FIG. 8 is another perspective view of the first embodiment, showing the illumination part in lighted condition;
FIG. 9 is a perspective view of an armrest showing a second embodiment of our new design;
FIG. 10 is a front view of the second embodiment;
FIG. 11 is a rear view of the second embodiment;
FIG. 12 is a left side view of the second embodiment;
FIG. 13 is a right side view of the second embodiment;
FIG. 14 is a top view of the second embodiment;
FIG. 15 is a bottom view of the second embodiment; and,
FIG. 16 is another perspective view of the second embodiment, showing the illumination part in lighted condition.
